UNITED STATES PATENT OFFICE.

WILLIAM H. SAART, OF ATTLEBOROUGH, MASSACHUSETTS, ASSIGNOR TO
THE JAMES E. BLAKE COMPANY, OF SAME PLACE.

DESIGN FOR A BRACELET.

SPECIFICATION forming part of Design No. 32,273, dated February 27, 1900.

Application filed January 20, 1900. Serial No. 2,210. Term of patent 7 years.

To all whom it may concern:

Be it known that I, WILLIAM H. SAART, a citizen of the United States, residing at Attleborough, in the county of Bristol and State of Massachusetts, have invented and produced a new and original Design for a Bracelet, of which the following is a specification, reference being had to the accompanying drawings, forming part thereof.

Figure 1 is a side view of the bracelet, showing my design. Fig. 2 is an edge view of the same.

The leading feature of my design consists in two round strands or members, one of which has a plain and the other an ornamented surface, presenting to the eye the appearance of two round strands twisted together to form a bracelet.

In the drawings, 3 indicates the plain member and 4 the ornamented member, both 20 having spirally-disposed convex surfaces. The ornamentation of the member 4 consists of the leaf-scrolls 5, as clearly shown in Fig. 1.

Having thus described my invention, what I claim as new, and desire to secure by Letters 25 Patent, is—

The design for a bracelet herein shown and described.

In testimony whereof I have signed my name to this specification in the presence of two subscribing witnesses. 30

WILLIAM H. SAART.
